United States Patent Office.

CHARLES E. LATTIN, OF BIRMINGHAM, CONNECTICUT, ASSIGNOR TO HIMSELF AND JOHN R. LATTIN.

Letters Patent No. 70,340, dated October 29, 1867.

IMPROVEMENT IN FLUSH-BOLT.

The Schedule referred to in these Letters Patent and making part of the same.

TO ALL WHOM IT MAY CONCERN:

Be it known that I, CHARLES E. LATTIN, of Birmingham, in the county of New Haven, and State of Connecticut, have invented a new Improvement in Flush-Bolts for Doors, &c.; and I do hereby declare the following, when taken in connection with the accompanying drawings and the letters of reference marked thereon, to be a full, clear, and exact description of the same, and which said drawings constitute part of this specification, and represent, in—

Figure 1, a front view,

Figure 2 a side view, and in

Figures 3 and 4 sections, on line $z z$, to illustrate the operation.

This invention relates to an improvement in that class of bolts for doors, &c., commonly called flush-bolts, or such as have the operative parts of the bolt flush with the face of the plate or case, and consists in the peculiar construction and arrangement of that part by which the bolt is moved.

To enable others to construct and use my improvement, I will proceed to describe the same, as illustrated in the accompanying drawings.

A is a plate, constructed so as to receive the bolt B, and, while it forms bearings C for the bolt, it encloses or covers the bolt when placed upon the door, or to whatever the bolt is applied. Centrally, or nearly so, in the plate A, I form an opening to receive a plate, D; the said plate D pivoted upon the under side of the plate A at a , as seen in fig. 2, and as denoted by broken lines, fig. 1, and so that when lying flat and at rest, as in fig. 2, the surfaces of the plate A and the plate D are flush and even. The said plate D is formed with arms, d , and it may be depressed at either side from the pivots, as seen in figs. 3 and 4, and when depressed, as in fig. 3, in the direction denoted by the arrow, the depressed arm d strikes upon the bolt, so that by the continued movement of the plate D the bolt is thrown out, as seen in fig. 3, and when in like manner depressed in the opposite direction, as seen in fig. 4, the other arm, d , comes in contact with the bolt, and so as to draw it in, as seen in fig. 4. A spring, E, bears upon the plate D, so that when free and at rest the plate D lies flat and flush, and yet so that it may be easily depressed in either direction, as occasion may require.

Having therefore thus fully described my invention, what I claim as new and useful, and desire to secure by Letters Patent, is—

The combination of the plate D in the plate A and the bolt B, constructed and arranged so as to operate substantially as herein set forth.
